UNITED STATES PATENT OFFICE

ARTHUR F. BRUCKNER AND GEORGE SAYRE, OF ELGIN, ILLINOIS.

CURTAIN-FASTENING DEVICE.

No. 854,073.

Specification of Letters Patent.

Patented May 21, 1907.

Application filed September 14, 1906. Serial No. 334,594.

To all whom it may concern:

Be it known that we, ARTHUR F. BRUCKNER and GEORGE SAYRE, citizens of the United States, residing at Elgin, in the county 5 of Kane and State of Illinois, have invented certain new and useful Improvements in Curtain-Fastening Devices, of which the following is a specification.

This invention relates to improvements in 10 curtain fasteners adapted especially for use on vehicles.

The principal objects of our improvements, 15 is to produce a fastener that will be strong and durable, that will securely hold the curtain, that will not be liable to become inoperative from exposure to the elements, and that will present a neat appearance.

A further object is to produce a button 20 that may be quickly and easily attached to different parts of the frame or body of a vehicle and that may be readily renewed should it become broken or damaged.

Having these special objects and others of 25 general utility in view, we have produced the button or curtain fastener shown in preferred forms in the accompanying drawing in which:—

Figure 1 is a plan view of one of our improved fasteners applied to a curtain, a fragment of the latter being shown; Fig. 2 is a horizontal section through the fastener and curtain shown in Fig. 1; Fig. 3 is a horizontal section showing a modification of our fastener and the method of attaching same to a 30 portion of a vehicle; Fig. 4 shows in elevation and section a slightly modified form of fastener; Fig. 5 is a top plan view of the fastener shown in Fig. 4; Fig. 6 is an elevation showing a modified method of attaching the 35 fastener, and Fig. 7 is a horizontal section through the fastener shown in Fig. 6.

Referring to the details of the drawing as 40 shown in Figs. 1 and 2, the base plate 3 of the fastener is provided with screw holes 4 through which the attaching screws 19 (Fig. 4) are passed. The plate 3 is formed integrally with the cylindrical domelike body portion 5 the side walls of which are drilled 45 at opposite points to form holes 8 in which are slidably arranged studs 9 having heads 10 on their inner ends. The center of the dome 7 of the body portion is drilled vertically to provide a hole for the stem 12 of the plunger 11 which is loosely mounted 50 within the chamber 7, and rests upon the outer end of an expansion coil-spring 14, the

tension of which is exerted to hold the plunger in the upper part of the chamber 7, whereby the stem 12 and the studs 9 will be normally projected from the surface of the 60 dome. The plunger is formed with a neck or annular grooved portion 13, into which the heads of the studs slide when the stem 12 is depressed, and pressure is brought to bear on the outer ends of the studs such as would 65 be incident to an attempt to pull the gromet 16 over the dome.

A screw-plug 15 engages a suitable opening provided therefor in the center of the base 3, and forms a removable bearing for the inner 70 end of the spring 14.

Instead of forming the plug as above set forth, it may be constructed as shown in Fig. 3, 4, and 7. In Fig. 3, the plug 21 is provided with an integral stem 22 which is 75 adapted to be passed through a hole, as 23, drilled in the woodwork or frame of the vehicle, and has its outer end threaded, as at 24, and equipped with a milled nut 25. The stem, when so constructed, serves as additional attaching means for the fastener, the 80 principal means being the screws 19, 19.

If desired, the plug 27 may have a plain or non-threaded stem 28, as shown in Fig. 4 which may be passed through the woodwork 85 and have its end headed over to hold it against displacement. Or the stem may be formed as a screw 30 for the plug 29, which is threaded and inserted in the base of the fastener in the manner already described. 90

In lieu of forming the plunger with a convex surface and a groove 13, we may form its exterior concave as at 13^a in Figs. 3 and 7, the reduced outer portion serving to permit the retraction of the studs 9 in the manner 95 described.

It will be noted that the outer ends of the studs are rounded, thus facilitating attaching and detaching the curtain 17, the inner edges of the gromet 16 passing easily over 100 the ends of the studs when the latter are retracted. The button or extension 12 of the plunger is easily retracted by pressure of the finger of the operator or by the flange of the gromet and the dome like contour of the 105 fastener renders easy the application of the gromet. Should the studs become worn from constant use, it is only necessary to detach the fastener, remove the plug 15, the spring and plunger and insert new studs. 110 Should the stem of a plug become broken, a new plug can be readily substituted. Other

utilities in our device will be apparent to those skilled in the art.

Having thus described our invention what we claim is:—

- 5 1. A fastening device, comprising a suitable base, a chambered body portion having axial and lateral openings in its walls, studs removably and slidably arranged in the lateral openings, a plunger removably arranged 10 in the chambered portion, bearing against said studs, and having an extension projecting through the axial opening, and a spring bearing on said plunger.
- 15 2. A fastening device comprising a suitable base, a chambered body portion having axial and lateral openings in its walls, studs slidably arranged in said lateral openings a plunger slidably arranged in said axial opening and normally bearing against said studs, 20 a spring engaging said plunger, and a removable plug inserted in said base and forming a bearing for said spring.
- 25 3. A fastening device comprising a suitable base, a chambered body portion having axial and lateral openings therein, studs slidably arranged in said lateral openings, a plunger slidably arranged in said axial opening and bearing against said studs, a spring engaging said plunger to hold it in its projected 30 position, a screw plug forming a closure for said chambered portion and provided with

an extension adapted to be secured to a suitable support.

4. A fastening device comprising a suitable base having an opening therein, a body portion projecting from said base with lateral openings therein, and having a chamber registering with said opening, a plug removably mounted in said opening and having a stem projecting therefrom, a coil-spring arranged in said chamber and bearing on said plug, a plunger mounted in said chamber, having a portion projecting through said body portion, and having its inner end bearing on said spring, and studs slidably mounted in said lateral openings and having their inner ends bearing on said plunger. 40

5. In a fastening device, a chambered body having axial and lateral openings, a push member slidably mounted in said body and consisting of a plunger having a convex portion, a recessed portion and an extension, said extension projecting through said body, and means for normally holding said extension in its projected position. 50

In testimony whereof we affix our signatures in presence of two witnesses.

ARTHUR F. BRUCKNER.
GEORGE SAYRE.
